BOX CONSTRUCTION

Irving A. Deline, Denver, Colo.

Application February 5, 1931, Serial No. 513,540
Renewed December 6, 1932

5 Claims. (Cl. 229—15)

This invention relates to box construction and while more particularly applicable to candy boxes, dresser boxes, and similar ornamental boxes, it will be found useful in many other 5 adaptations.

The principal object of this invention is to provide a simple and efficient construction for boxes of this character which will divide the box into compartments and though constructed of 10 relatively thin material, such as cardboard, will provide relatively thick partitions and walls for the compartments.

Another object of the invention is to so construct the box that the above object can be accomplished with a minimum number of separate 15 pieces or parts.

A further object of the invention is to provide a box of this character with a secret or concealed drawer or recess in which valuables may be hid- 20 den.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 illustrates a complete box in which the invention is embodied.

Fig. 2 illustrates what will be herein designated 35 the partition board before the same is folded.

Fig. 3 illustrates what will be herein designated the compartment board as it appears before folding.

Fig. 4 illustrates the outer box ready to receive 40 the folded partition and compartment boards.

Fig. 5 illustrates the folded partition board ready for insertion in the box.

Fig. 6 illustrates the folded compartment boards ready for insertion in the partition board.

Fig. 7 is a cross sectional view through the completed box taken on the line 7—7, Fig. 1.

Fig. 8 is a detail view illustrating a secret drawer which may be embodied in the invention.

The outer box of the invention, designated at 50 10, can have any suitable design, shape, or finish and may be provided with a suitable lid 11.

The compartments and partitions are formed within the box 10 by means of a partition board 12 and compartment boards 17. The partition board 12 is formed with side flaps 13 and end

flaps 14 arranged to fold at right angles to the board 12 along the broken lines A of Fig. 2. The openings for the compartments are formed by means of diagonal cuts 15 which form substantially triangular compartment flaps 16 which, 60 when folded along the broken lines B of Fig. 2, form openings for the compartments.

When ready for insertion in the box 10, the partition board 12 appears as illustrated in Fig. 5. If desired the open corners of the exterior 65 15 may be bound with gummed tape. This is not absolutely necessary, however, since these corners will be retained in position by the box 10.

The compartment walls are formed by means of the compartment board 17 which is cut with 70 side flaps 18 and end flaps 19 all of which fold at right angles to the plane of the board along the fold lines C, Fig. 3.

When ready for insertion in the partition board 12 the compartment boards are folded as 75 shown in Fig. 6 and are forced into the compartment openings in the partition board 12. If desired, the open corners of the compartment boards can be closed by gummed tape. This is not absolutely necessary, however, as the partition board 12 will hold these corners in place 80 after the compartment boards have been placed in position.

When the three members of Figs. 4, 5, and 6 have been assembled the upper part of the partitions and walls is covered by means of a gummed binding tape 20 in order to conceal the joints and edges of the various parts.

It will be noted that when assembled the box has the appearance of having heavy massive walls 90 and partitions. This greatly enhances the attractiveness to the purchaser, acts to increase the size of the box without increasing the net contents, serves as a cushion for the contents, and also acts to insulate the contents from changes 95 in temperature, etc.

The box also has an additional feature, for instance, the hollow walls and partitions form secret chambers within which articles may be hidden and to which access may be had by simply 100 lifting the partition board 12 from the box 10.

It has been found desirable in order to prevent articles from falling from these hidden recesses, to provide relatively narrow vertical drawers 21 of a size to fit snugly into the hollow partitions. If the drawers 21 are used, the flaps 13 and 14 of the partition board can be cut away as indicated in broken line at 22, Fig. 5, in order to provide room for a finger hold for withdrawing the 110 drawers.

While a specific form of the improvement has been described and illustrated herein, it is desired to be understood that the same may be varied, within the scope of the appended claims, 5 without departing from the spirit of the invention.

Having thus described the invention, what is claimed and desired secured by Letters Patent is:—

- 10 1. A construction for candy boxes and the like comprising: an outer box; a partition board; flaps formed on said partition board and adapted to extend downwardly along the inner faces of said outer box; triangular flaps formed on said 15 partition box adapted to fold downwardly in spaced relation to said first flaps; open-topped, box-like compartment members adapted to fit within the opening formed by said triangular flaps; and a binding covering the edges of said 20 compartment members and securing the latter to said partition board.
2. A construction for candy boxes and the like comprising: an outer box; a partition board; flaps formed on said partition board and adapted to extend downwardly along the inner faces of said outer box; triangular flaps formed on said 25 partition box adapted to fold downwardly in spaced relation to said first flaps; open-topped, box-like compartment members adapted to fit 30 within the opening formed by said triangular flaps; said compartment members comprising: compartment boards; flaps formed on said compartment boards and adapted to fold upwardly therefrom so as to lie flat against the triangular 35 flaps of said compartment board; and a binding tying the compartment board flaps to said partition board.
3. A construction for boxes comprising: an outer box; a compartment board; flaps formed 40 on said compartment board around the periphery thereof and adapted to extend downwardly within said outer box against the inner faces of the walls thereof; a series of triangular flaps formed in said compartment board and adapted to fold 45 downwardly in spaced relation to said first flaps and to each other so as to form relatively thick walls and partitions; a series of compartment boards; flaps formed on said compartment boards and extending upwardly therefrom so that when 50 said compartment boards are placed within the

openings formed by said triangular flaps the flaps of the two boards will lie flat against each other so as to leave hollow partitions and walls; and a binder surrounding the upper portion of said partitions and walls so as to bind said compartment boards to said partition board. 80

4. A construction for boxes comprising: an outer box; a compartment board; flaps formed on said compartment board around the periphery thereof and adapted to extend downwardly within said outer box against the inner faces of the walls thereof; a series of triangular flaps formed in said compartment board and adapted to fold 85 downwardly in spaced relation to said first flaps and to each other so as to form relatively thick walls and partitions; a series of compartment boards; flaps formed on said compartment boards and extending upwardly therefrom so that when 90 said compartment boards are placed within the openings formed by said triangular flaps the flaps of the two boards will lie flat against each other so as to leave hollow partitions and walls; a binder surrounding the upper portion of said partitions and walls so as to bind said compartment boards to said partition board, said bound together boards being removable from said outer box so as to allow access to said hollow partitions and walls. 95

5. A construction for boxes comprising: an outer box; a compartment board; flaps formed on said compartment board around the periphery thereof and adapted to extend downwardly within said outer box against the inner faces of the walls thereof; a series of triangular flaps formed in said compartment board and adapted to fold 100 downwardly in spaced relation to said first flaps and to each other so as to form relatively thick walls and partitions; a series of compartment boards; flaps formed on said compartment boards and extending upwardly therefrom so that when 105 said compartment boards are placed within the openings formed by said triangular flaps the flaps of the two boards will lie flat against each other so as to leave hollow partitions and walls; a binder surrounding the upper portion of said partitions and walls so as to bind said compartment boards to said partition board, said bound together boards being removable from said outer box so as to allow access to said hollow partitions and walls. 110
